US0D1041445S

(12) **United States Design Patent** (10) Patent No.: **US D1,041,445 S**
(45) Date of Patent: ** Sep. 10, 2024

(54) **EARPHONES WITH CHARGING CASE**

(71) Applicant: **Shenzhen Beijiabi Technology Co., Ltd.**, Shenzhen (CN)

(72) Inventor: **Lingzhong Zhao**, Shenzhen (CN)

(73) Assignee: **Shenzhen Beijiabi Technology Co., Ltd.**, Shenzhen (CN)

(**) Term: **15 Years**

(21) Appl. No.: **29/873,999**

(22) Filed: **Apr. 12, 2023**

(51) LOC (14) Cl. **14-01**

(52) U.S. Cl.

USPC **D14/223**; D13/108

(58) Field of Classification Search

(57) **CLAIM**

The ornamental design for earphones with charging case, as shown and described.

DESCRIPTION

FIG. 1 is a top perspective view of a case of the earphones with charging case, showing my new design, the case is shown separately for ease of illustration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of the earphones with charging case, in an open position thereof;

FIG. 9 is a top perspective view of a case, of earphones with charging case, in an open position thereof;

FIG. 10 is a top perspective view of an earphone, of the earphones with charging case thereof, shown separately for ease of illustration;

FIG. 11 is a front view thereof;

FIG. 12 is a rear view thereof;

FIG. 13 is a right side view thereof;

FIG. 14 is a left side view thereof;

FIG. 15 is a bottom view thereof;

FIG. 16 is a top view thereof;

FIG. 17 is a top perspective view of an earphone, of earphones with charging case thereof, shown separately for ease of illustration;

FIG. 18 is a front view thereof;

FIG. 19 is a rear view thereof;

FIG. 20 is a right side view thereof;

FIG. 21 is a left side view thereof;

FIG. 22 is a bottom view thereof; and,

FIG. 23 is a top view thereof.

The broken lines in the drawings illustrate the portions of the earphones with charging case, which form no part of the claimed design.

1 Claim, 23 Drawing Sheets
